UNITED STATES PATENT OFFICE.

JOSEPH EIFEL, OF CHICAGO, ILLINOIS.

WRENCH.

1,181,654.

Specification of Letters Patent.

Patented May 2, 1916.

Application filed June 26, 1912. Serial No. 706,079.

To all whom it may concern:

Be it known that I, JOSEPH EIFEL, a citizen of the United States, and a resident of Chicago, in the State of Illinois, have invented certain new and useful Improvements in Wrenches, of which the following is a specification.

My present invention relates to wrenches in general and more particularly to wrenches having variable jaw openings, and has special reference to the provision of an improved wrench embodying the most valuable features of wrenches of a number of different types known to me, and avoiding the defects thereof.

The principal objects of my present invention are the provision of a wrench having jaws one of which may be rapidly moved relatively to the other, a wrench thus characterized which will not tend to work open in handling, thus requiring repeated settings or adjustments during a single operation, one which will have small crushing effect tending to abrade, flatten or otherwise disfigure articles upon which it is used; the provision of an improved plier form wrench adapted for wide separation of the jaws without concurrent wide opening of the handles and one wherein relatively slight manipulation is required either in moving the article acted upon or in obtaining a fresh hold thereupon; the provision of a wrench wherein the parallelism of the jaws may be readily maintained irrespective of the size of the object operated upon; the provision of a wrench wherein the number of contact points of the jaws thereof with the article operated upon may be increased and generally to provide an improved and more efficient type of wrench than is at this time available, together with such further and additional objects as may hereinafter appear.

In gaining the objects above mentioned, as well as certain further benefits and advantages to be below pointed out, I have provided the constructions illustrated in the accompanying drawings, wherein—

Figure 1 is an elevational view illustrative of my invention embodied in a wrench wherein, as shown, adjustable pliers having parallel jaws are provided. Fig. 2 is an edge view of the wrench of Fig. 1; Fig. 3 is a sectional view taken on the line III—III of Fig. 1; Fig. 3^a is an elevational view of a modified form of jaw construction; Fig.

4 is an elevational view illustrative of my invention embodied in a wrench wherein, as shown, adjustable pliers having jaws which are variable not only in their degree of separation, but also in the degree of angularity of their operative relation to the handle, are provided; Fig. 5 is an edge view of the wrench of Fig. 4, partly in section taken on the line V—V of Fig. 4; Figs. 6 and 7 are elevational views of modified forms of jaws applicable to the wrenches of the types of Figs. 1 and 4; Figs. 8 and 9 are respectively an edge view and an elevational view illustrative of a modified form of construction; and Figs. 10 and 11 are sectional views thereof, taken respectively on the line X—X of Fig. 8 and XI—XI of Fig. 10.

Referring now more particularly to the device of Figs. 1, 2 and 3 it will be observed that in this embodiment of my invention wherein I have shown a form of wrench, which is adaptable for use as a parallel and adjustable plier, the shank 110 has formed at one end a handle 111 and at the opposite end a jaw 112 and that the jaw 112 is slotted as indicated at 113 to allow the shank 114 provided with a jaw 115 to slidably move therein and support the jaw 115 in parallelism with the jaw 112. The shank 114 of the jaw 115 is provided with a toothed rack 116 and for moving the said jaw 115 relatively to the jaw 112 I employ an operating lever 117 pivoted to the lever 110, as indicated at 118, engaging slots 120 in said handle 110, and provided with a segmental gear 122 engaging the rack 116, which is supported by means of a pin 119 in slot 123. As an anti-friction device between the rack 116 and the shank 110 I employ a roller bearing indicated at 124. For holding the parts in adjusted position, I employ a ratchet toothed pawl 137 pivoted at 138 in the handle 111 and adapted to engage a complementary ratchet toothed rack 139 carried by the handle 117, a spring 140 acting upon an extension 137^a of the pawl serving for normally holding the pawl and rack in engagement, and a sliding block 138^a, having an inclined surface, being provided for moving the pawl out of engagement with the ratchet 139 when it is desired to move the handles apart.

In the operation of the device above described, it will be observed that upon moving the block 138^a inward, the handles 111 and 117 may be separated, the handle 117

moved sidewise and inward disengaging the segment 122 from the rack 116 thus permitting the desired adjustment of the jaws 112 and 115. If an ordinary close fit is desired 5 the handle may then be moved until the segment 122 engages the rack 116, when the handle may be locked. If, however, it be desired to strongly grip the bolt, pipe or other article to be acted upon the handle 10 117 may be moved a short distance outward around the pivot 118 and then into a position where the segment 122 engages the rack 116 and then the handles 117 and 111 may be caused to approximate, moving the jaws 15 115 and 112 toward each other, though without disturbance of their parallelism. It will thus be noted that a great variation of the opening of the jaws according to the size of the object acted upon may be attained 20 in the use of the wrench above described, but at the same time practically instantaneous adjustment both of the amount of the pressure and of the opening of the jaws may likewise be attained without excessive 25 separation of the operating handles.

Referring now more particularly to the device of Figs. 4 and 5 it will be observed that I have here illustrated a wrench embodying my invention in the form of a pair 30 of pliers, wherein the gripping faces of the jaws may be arranged in any required degree of angularity between parallelism and a right angle relatively to the longitudinal axis of the operating handles, and by suitable modification of their position, or the 35 use of the jaws illustrated in Figs. 6 and 7 may readily be adapted for one or more of the following purposes, an adjustable wrench, adjustable pliers, parallel pliers, adjustable pipe tongs, wire cutter, etc. In this embodiment of my invention it will be obvious upon examination of the drawings, that the arrangement of jaws is similar to that of the wrench of Figs. 1, 2 and 3, save 40 that instead of direct engagement between the segment and rack there disclosed, I here interpose a gear wheel whereby certain angularities of adjustment are made possible, all as now to be described. It will be seen 45 that in my present construction I employ a shank 210 provided at one end with a handle 211 and at the opposite end with a jaw 212, pivoted thereto at 212^a and slotted as indicated at 213 for the reception of the 50 shank 214 which is provided with a jaw 215 and engages by means of a pin 219 a slot 223 in said jaw 212, a roller bearing 224 being interposed between the jaw 212 and the shank 214. On the pivot pin 212^a is 55 rotatably mounted a pinion having a toothed periphery 222 engaging a rack 216 formed on the shank 214, and likewise engaging a segmental rack 222^a formed on the operating lever 217, which has pivotal engagement 60 with the shank 210 as indicated at 218, and

is slidable relatively thereto by means of the slot 220 in which said pin 218 is movably carried.

For normally preventing movement of the jaw 212 relatively to the shank 210 I provide on the extensions 275 of said jaw 212 toothed segments 276 which engage complementary toothed segments 277 on a lever 278 movable relatively to the hollow handle 210, but normally held in the position shown 75 by means of a spring 279, such lever 278 being bifurcated and the bifurcated portions thereof being carried on the pin 218. For holding the handles 211 and 217 in the relative position shown I employ a pawl 287 pivoted at 288 in the handle 217 and normally engaging the ratchet 289, such pawl being provided with an extension 287^a against which the spring 240 acts in order to maintain the engagement with the ratchet, 80 a sliding block 288^a being employed to release the engagement when desired.

In the operation of the device above described it will be observed that moving the slide 288^a disengages the pawl 287 from the 90 ratchet 289 and allows the handles 217 and 211 to be separated. Upon moving the handle 217 inwardly, and pressing the lever 278 toward the handle 210, thereby disengaging the handles 217 and 210 from the pinion 222, and the jaws 212 respectively, the jaws 212 and 215 may be varied in the amount of their separation. Upon releasing pressure upon the lever 278 the toothed portion 277 thereof will again engage with the 95 toothed portion 276 of the jaw 212 fixing it in position relatively to said lever 210, and upon the lever 217 being moved to the position shown the toothed segment 222^a thereof will engage the pinion 222 in turn acting 100 upon the rack 216 and moving the jaw 215 toward the jaw 212.

Where desirable the device of Fig. 4 may be provided with jaws having cutters as indicated at 45^b, 46^b, in Fig. 6, or with jaws 110 curved or serrated, or both, as indicated at 47^b, 48^b, in Fig. 7.

Referring now more particularly to the device of Figs. 8 to 11 it will be observed that I have here illustrated a wrench embodying my invention in another form of adjustable parallel pliers, wherein a shank 310 has formed at one end a handle 311 and at the opposite end a jaw 312, and that the jaw 312 is slotted as indicated at 313 to allow the shank 314 provided with a jaw 315 to move therein and support the jaw 315 in parallelism with the jaw 312. The shank 314 is provided with toothed means for engagement with the shank of the jaw 315, here shown as the link 316^a, provided with ratchet teeth 316 engaging teeth 316^b on the shank of the jaw 315, the said shank 314 engaging the said link 316^a by means of a ball extension 322 engaging a socket 322^a, the 120 125 130

toothed engagement thus formed being similar in operation to that above described in connection with the device of Fig. 4. For moving said jaw 315 relatively to the jaw 312 I employ an operating lever 317 formed on the shank 314 which is pivoted to the lever 310 as indicated at 318, and as an anti-friction device between the jaws 312 and 315 I employ a roller bearing indicated at 324. For normally preventing movement of the jaw 315 relatively to the link 316^a, and thereby transverse lineal movement of such jaw relatively to the shank 314 and consequently separation of the jaws 312 and 315, I employ a lever 378 pivoted to the handle 310 as indicated at 380, and engaging by means of a pin 376 a slot 377 formed in the link 316^a, the shank 310 being slotted as indicated at 381 to permit movement of said pin in the shank 310. For normally holding the lever 378 in position and thereby the link 316 in engagement with the toothed surface of the jaw 315, I employ a slide 379 engaging a slot 379^a and acting on one surface of the end of said lever 378, a spring 382 bearing on the opposite surface thereof serving to throw the toothed portions of the members 316 and 315 out of engagement when said slide is moving toward the jaws, thereby permitting adjustment of the jaw 315 relatively to the jaw 312.

To permit a partial movement of the lever 378 sufficient merely to allow a ratcheting of the toothed portion of the member 315 upon the toothed portion of the member 316, a notch 383 is provided in the lever 378 allowing it to be partially rotated about the pivot point 380, thereby moving the link 316^a toward the end of the handles, but if entire disengagement is desired the slide should be moved to the right so that the boss 384 formed thereupon will approximate the position of the surface 385 of such lever. A spring 386 normally serves to aid in holding the link 316^a in contact with the jaw 315 and a pin 387 passing through the slot 377 serves to limit the movement of said link toward said jaw.

From the foregoing description of the construction and operation of the several embodiments of my invention it will be observed that all of the several types disclosed are provided with means whereby the jaws may be instantly opened and closed to a limited extent for shifting relatively to the work, thereby making it feasible to utilize notches such as 50—51 for the purpose of engaging the corners, as well as flat faces of nuts, giving a much firmer hold thereupon.

It will thus be observed that by the use of the several embodiments of my invention illustrated I am able where it is desirable to engage a nut on parallel faces, on opposed corners, or on a corner opposed to a face,

with more holds and thus with firmer engagement than is possible with any other form of a wrench known to me. Since the pressure applied upon closing the wrench may be very readily varied, it is obvious that the pressure applied to any nut, pipe or other object worked upon may be gaged to suit conditions with the greatest of facility.

Other advantages of my present invention will be apparent to those who are skilled in the art to which it pertains.

Having thus described my invention and illustrated its use, what I claim as new and desire to secure by Letters Patent is:

1. A device of the character described comprising, in combination, a pair of pivoted operating levers provided with coöperating jaws, one of said jaws being movable transversely of the longitudinal axis of the device and relatively to its lever and having rack and gear means for releasable engagement therewith whereby the extent of the jaw opening may be varied.

2. A device of the character described comprising, in combination, a pair of operating levers provided with coöperating jaws and having means for engagement whereby the levers are movable pivotally and lineally relatively to each other, one of said jaws being movable transversely relatively to its lever and having means for toothed engagement therewith whereby the extent of the jaw opening may be varied.

3. A device of the character described comprising, in combination, a pair of operating levers provided with coöperating jaws and having means for engagement whereby the levers are movable pivotally and lineally relatively to each other, one of said jaws being movable relatively to its lever and having means for toothed engagement therewith whereby the extent of the jaw opening may be varied, and means for normally preventing lineal relative movement of levers.

4. A device of the character described comprising, in combination, a pair of pivoted operating levers provided with coöperating jaws, means for adjusting the position of one of said levers relative to its jaw, means between the levers and intermediate the ends of the levers for releasably locking said levers against relative movement when adjacent to each other, and means for releasing said locking means.

5. A device of the character described comprising, in combination, a pair of pivoted operating levers provided with coöperating jaws, and means for releasably locking them in position including a pawl and ratchet between the levers and disposed between said levers intermediate their ends.

6. A device of the character described comprising, in combination, a pair of pivoted operating levers provided with coöp-

erating jaws, means disposed between the levers for releasably locking them in position including a ratchet on one of said levers, and a pawl pivoted to the other of 5 said levers and having an arm, and means independent of the pawl for tripping said pawl.

7. A device of the character described comprising, in combination, a pair of pivoted operating levers provided with coöperating jaws, means disposed between the levers for releasably locking them in position including a ratchet on one of said levers, and a spring pressed pawl pivoted to 10 the other of said levers and having an arm, and means acting on said arm for tripping said pawl.

8. A device of the character described comprising, in combination, a pair of pivoted operating levers provided with coöperating jaws, means disposed between the levers for releasably locking them in position including a ratchet on one of said levers, and a pawl pivoted to the other of 15 25 said levers and having an arm, and a slide for tripping said pawl.

9. A device of the character described comprising in combination a pair of pivoted operating levers provided with coöperating jaws, one of said jaws being operatively movable relatively to its lever and both the lever and the jaw being provided with means for engagement, an intermediate member engaging said means whereby the 30 35 relative position of the jaws may be varied, and means for normally holding the jaws in predetermined operative relation relative to each other.

10. A device of the character described comprising, in combination, a pair of pivoted levers provided with coöperating jaws, and having means for engagement whereby the levers are movable pivotally and lineally relatively to each other, one 40 45 of said jaws being movable relatively to its lever and both the lever and the jaw being provided with means for engagement, an intermediate member engaging said means whereby the relative position of the jaws may be varied, and means for normally holding the jaws in predetermined operative relation relative to each other.

11. A device of the character described comprising, in combination, a pair of pivoted levers provided with coöperating jaws, and having means for engagement whereby the levers are movable pivotally and lineally relatively to each other, one 50 55 of said jaws being movable relatively to its

lever and both the lever and the jaw being provided with means for engagement, an intermediate member engaging said means for engagement whereby the relative position of the jaws may be varied, and means for normally holding the jaws in predetermined operative relation relative to each other including engaging means for one of said jaws and a third lever provided with means for engaging said last mentioned means. 65 70

12. A device of the character described comprising, in combination, a pair of operating levers provided with coöperating jaws, and having means for engagement whereby the levers are movable pivotally and lineally relatively to each other, one of said jaws being movable relatively to its lever and both the lever and the jaw being provided with means for engagement, an intermediate member engaging said means for engagement whereby the relative position of the jaws may be varied, and means for normally holding the jaws in predetermined operative relation relative to each other including engaging means on one of 80 85 said jaws and a third lever provided with engaging means engaging said last mentioned engaging means and a spring for maintaining such engagement.

13. A device of the character described comprising in combination, a pair of pivoted levers provided with coöperating jaws, one of said jaws being movable relatively to the other thereof and to its lever and provided with a rack portion, and a gear 90 95 for releasably engaging said rack portion whereby the jaws may be held in predetermined operative relation relatively to each other.

14. A device of the character described comprising in combination, a pair of pivoted levers provided with coöperating jaws, one of said jaws being movable relatively to the other thereof and to its lever and transversely of the longitudinal axis of the 100 105 device and provided with engaging teeth, and a plurality of teeth on said last-mentioned lever adapted to engage the teeth on said movable jaw whereby the jaws may be held in predetermined operative relation relatively to each other.

In testimony whereof I have hereunto signed my name in the presence of the two subscribed witnesses.

JOSEPH EIFEL.
